UNITED STATES PATENT OFFICE

GEORGE W. DUNHAM, OF UTICA, NEW YORK, ASSIGNOR TO THE WHIRLDRY CORPORATION, OF UTICA, NEW YORK, A CORPORATION OF NEW YORK

MULTIPLE-COMPARTMENT LAUNDRY MACHINE

Application filed April 23, 1928. Serial No. 104,023.

The invention relates to laundry machines, and more particularly to those of the type performing both washing and drying operations.

5 According to the invention, a laundry machine is provided in which a batch of laundry may be subjected to several operations, such as washing, rinsing, blueing, drying, etc. without removing the laundry from the machine and without discarding any of the several liquids used for performing these operations. This is accomplished by providing the machine with a plurality of compartments for holding the several liquids. Also 15 appropriate means are provided for directing the several liquids into the tub in which the laundry is placed or into any one of the compartments, as may be necessary or desirable.

Various other objects and advantages of 20 the invention will be obvious from the following particular description of one form of mechanism embodying the invention or from an inspection of the accompanying drawings; and the invention also consists in certain new and novel features of construction and combinations of parts hereinafter set forth and claimed.

In the drawings:

Fig. 1 represents an elevation with parts 30 broken away illustrating a laundry machine made according to the teachings of the invention;

Fig. 2 is a fragmentary view partly in section taken on the line 2—2 of Fig. 1;

35 Fig. 3 is a plan view taken on the line 3—3 of Fig. 2 showing the construction of the partition in the tank;

Fig. 4 represents an elevation partly in section illustrating a modified form; and

40 Fig. 5 is a plan view showing the construction of the compartments, taken on the line 5—5 of Fig. 4.

In the following description and in the claims parts will be identified by specific 45 names for convenience, but they are intended to be as generic in their application to similar parts as the art will permit.

Referring now to the drawing, and more particularly to Figs. 1, 2 and 3, a laundry 50 machine is shown having a receptacle 1 of

the imperforate type for holding both the laundry and washing liquid thereby acting as a wash tub. This receptacle 1 may be rotated to discharge the laundry liquid from the laundry during centrifugal drying operations. 55

The laundry machine may comprise a lower tank section 2 supported by legs and having a bottom 3 which slopes downwardly toward the middle of the tank, at which point an opening 4 is provided. A horizontally disposed centrifugal type pump 5 may be secured to the bottom, the intake of the pump connecting with the opening 4 in the bottom 3. Secured to the lower side of the pump casing 5 may be a gear box 6 in which suitable gearing may be located for driving the several parts of the machine. An electric motor 7 may be supported from the bottom of the lower tank section 2 and may serve to drive 70 the gearing in the gear box 6 by means of the belt 8. Rising from the upper wall of the pump casing 5 may be a hollow pedestal 11 on the top of which the receptacle 1 is journaled. Suitable shafting may be provided 75 within the hollow pedestal 11 and in operative relation to the gearing in the gear box 6 for driving the receptacle 1. The particular mechanism in the gear box for driving the receptacle as well as the specific construction of the receptacle is disclosed in my co-pending application Serial No. 18,086, filed 80 March 25, 1925, on laundry machine and forms no part of the present invention.

A strainer 9 comprising a conical portion 85 fitting around the hollow pedestal 11, the conical portion having at its base a large radial flange, may be provided at the bottom of the lower section 2 to strain the water entering the pump 5.

Located above the lower tank section 2 is an upper tank section 12 which may be of larger diameter than the lower section 2. The upper section may comprise a generally cylindrical shell having a bottom wall 13 having a central opening 14 surrounded by an 95 standing annular flange 15 to form a gallery 16. In the bottom wall 13 of the gallery 16 may be a drain opening 17 in which may be 100

located a strainer or water purifying device 18.

The receptacle 1 which may be of the type having parts thereof imperforate for holding laundry and laundry liquid is preferably provided with a central hub 21 which fits over the top of the hollow pedestal 11. A guard ring 22 may be provided on the upper part of the receptacle for retaining the laundry 10 within the receptacle during the several laundry operations. A plurality of holes 23 may be provided in a periphery near the top for allowing laundry liquid to leave the receptacle during the several laundry operations.

Secured to the side of the lower tank section 2 may be a standpipe 24 which may comprise a riser tube 25 having a trap in the bottom and a lateral branch 26 connected to the 20 discharge of the pump 5 by means of a flexible tube 27. Telescoped within the riser tube 25 is a flow pipe 28 having a goose-neck nozzle 29 at its upper end. The flow pipe is open at its lower end and has an opening 30 near its 25 lower end which may register with the branch 26 in the riser tube as illustrated in Fig. 1.

The lower tank section 2 may have a false bottom 31 having an opening 34 in the center thereof. A partition made up of two sections 30 may be provided to divide the lower tank section 2 into two compartments A and B, each partition section comprising a vertical wall 35 and one-half of a cylindrical wall 36. When these two like sections are placed 35 together as shown in Fig. 3 a partition is formed comprising two diametrically opposed walls 35 and a cylindrical wall 37 spaced from the hollow pedestal 11. The cylindrical wall and also the annular flange 40 15 of the upper tank section 12 are spaced from the hollow pedestal so as to allow free lateral movement of the hollow pedestal. It will be understood that the hollow pedestal 11 may sway laterally slightly under some 45 conditions of operations such as when the receptacle is rotating.

The two compartments A and B may be provided with discharge openings 40 and 41 50 preferably in the false bottom 31 and which may be closed by means of stoppers 42 and 43. The stoppers 42 and 43 may have stopper rods 44 and 45 which may be guided in suitable guides 46 and 47, the stopper rods being pivoted to a cam lever 48 fulcrumed in ears 55 38 on the cylindrical wall 37.

On the lower surface of the bottom 13 of the upper tank section 12 an annular depending flange 51 may be provided to maintain the upper tank section in fixed lateral relation to the lower tank section. This flange 60 may be provided with a cam surface which co-operates with the end of the cam lever 48 to operate the stoppers 42 and 43 by relative rotation of the upper and lower tank sections. 65 A weight 52 may be provided on the stopper

rod 44 to close its stopper when the cam flange 51 is moved to allow the weight to become effective. Thus it will be seen that in the position shown in Fig. 1 the stopper in compartment B is closed while the stopper in compartment A is open. When the upper section 12 is rotated 180° the stopper in compartment A will be closed and that in compartment B will be open.

While the laundry machine may be operated to use the compartments A and B in a variety of ways, the following description of one method of operating the machine will be given. To wash the laundry, it may be placed in the receptacle 1 and the receptacle 75 filled with washing liquid and the laundry 80 agitated in any suitable way. If desired, sufficient washing liquid may be provided so that it may be pumped continually from the bottom of the lower section 2 to the top of the 85 receptacle 1. Fig. 1 indicates the position in which the several parts of the machine should be during washing operations. As the washing liquid is fed to the top of the receptacle it will overflow through the discharge openings 23 into the gallery 16 thence through the drain opening 17 into the compartment A, thence through the drain opening 40 into the intake of the pump 5, whence 90 it will be discharged by the pump through the standpipe 24 into the top of the receptacle. 95

After the washing operation is completed, the flow of water through the standpipe 24 may be stopped by shifting the flow pipe 28 so as to cause the solid wall of the flow pipe 28 to register with the branch 26 in the riser tube 25. The receptacle may then be rotated for centrifugal extraction to thoroughly remove the wash liquid, the wash liquid collecting in tank A since it cannot be discharged through the standpipe. After all of the wash liquid is collected in tank A the upper tank section may be rotated 180° causing the stopper in compartment A to close and the stopper in compartment B to open.

The laundry in the receptacle is now ready for rinsing. The rinse water may be added by a hose from the faucet (not shown) while the receptacle is rotating to effect an improved rinsing method which is disclosed and claimed in my co-pending application, Serial No. 101,026 filed April 10, 1926.

If it is desired not to save the rinse water it may be continually discharged out of the flow pipe clear of the machine, the flow pipe 120 28 then being in the position shown by the dotted lines, the open end of the flow pipe being above the branch 26. If, however, it is desired to save the rinse water, when sufficient rinse water is supplied to the machine, the laundry may be thoroughly rinsed by causing the rinse water to be continually circulated through the machine. The rinse water will be discharged from the discharge 125 openings 23 in the receptacle into the gallery 130

16, into tank B, into the pump 5, whence it will be pumped back into the receptacle 1. After the laundry is rinsed, the flow pipe

28 may be raised to stop the flow of water therethrough and the rinse water may then be collected in tank B, the rotation of the receptacle operating to extract all liquid from the receptacle by centrifugal extraction. The machine is now ready for washing the

10 next batch of laundry.

To wash the second batch of laundry the upper tank section 12 will be rotated to cause the stopper in tank B to close and the stopper in tank A to open. It will thus be seen that

15 the wash liquid which was stored in tank A is available for discharge by the pump 5 and standpipe 24 into the receptacle for washing.

Referring now to Figs. 4 and 5, the tank 60 in this modification is made in one section 20 with a gallery 61 secured to the cylindrical wall of the tank below the discharge openings 23 of the receptacle 1. The gallery may have a plurality of openings 62 and 63 which may be closed by manually operated stoppers 25 64 and 65.

A plurality of compartments in the bottom of the tank 60 is provided by setting two half tanks 66 and 67 into the main tank, the inner wall of each half tank having a semi-cylindrical part spaced from the hollow pedestal 11 to allow free lateral movement thereof. Each compartment C and D is located under a particular drain opening 62 and 63 into the gallery 61. The stoppers 68 and 69 for controlling the outlet of the liquid in the compartments C and D are operated manually by means of stopper rods 70 and 71 pivoted to a lever member 72. A rod 73 may extend from the lever member 72 out through 40 the side of the tank 60 to a handle 74 for operating the stoppers manually.

The operation of this modification will be obvious from the description given above. When it is desired to collect liquid in compartment C the stopper 68 will be closed and the stopper 64 above compartment C will be opened. Similarly, to collect liquid in compartment D, the stopper 69 in the bottom will be closed and the stopper 65 above compartment D will be opened. When circulation through the machine of the particular liquid which is stored in one of the compartments is desired, it is obvious that the two stoppers which are in the desired path will be opened.

55 Although the above described example of operation of the invention described the compartments as being used for the washing liquid and rinsing liquid, it is obvious that any two liquids which it is desired to save may be stored in these tanks, such as the washing and blueing liquids or any other liquids that happen to be used. Furthermore, it is obvious that any number of compartments may be provided for saving any number of liquids. The construction according to the in-

vention is very advantageous when the laundry is large and therefore must be divided into a number of batches.

The invention allows each bath to be put through the several operations of washing, rinsing, blueing and drying with great facility and without wasting any of the several liquids so that the same liquids may be used for a second and subsequent batches and without manually handling a given batch from its introduction into the machine to its removal therefrom.

While I have shown and described and have pointed out in the annexed claims certain novel features of the invention, it will be understood that various omissions, substitutions and changes in the forms and details of the device illustrated and in its operation may be made by those skilled in the art without departing from the spirit of the invention.

Having thus described my invention, I claim:

1. A laundry machine comprising a lower tank section having a plurality of storage compartments, an upper tank section having a bottom forming a gallery and mounted on said lower section, a receptacle rotatably mounted in said upper section, said bottom having a drain opening, and means whereby said upper section may be rotated relative to said lower section to move said opening over any one of said compartments.

2. A laundry machine comprising a tank having a bottom wall and a pedestal projecting from and supported by the bottom wall of said tank, a pump having its inlet connected to said bottom wall, a bottom partition spaced above said bottom wall and having a hole clearing said pedestal, an annular wall surrounding said pedestal and secured to said bottom partition, radial walls extending from said annular wall to the sides of said tank, said cylindrical and radial walls dividing said tank into two compartments.

3. A laundry machine comprising an upright, generally cylindrical tank having a transverse bottom wall, a pump having its inlet connected to said transverse bottom wall, a bottom partition spaced above said bottom wall to form a bottom compartment, transverse walls dividing said tank into a plurality of storage compartments above said bottom compartment, and means for selectively connecting said storage compartments with said bottom compartment.

4. A laundry machine comprising a lower tank section having a plurality of compartments therein, said compartments having drain openings, stoppers for said drain openings, an upper tank section having a gallery, a receptacle rotatably mounted in said upper section, said gallery having a drain opening in its bottom and having a cam surface, and devices controlled by movement of said cam surface for opening the stopper of the com-

4

partment over which said gallery drain opening is positioned.

5. A laundry machine comprising a lower section having a plurality of storage compartments, an upper section mounted on said lower section, a clothes receptacle rotatably mounted in said upper section, said upper section having a gallery to catch water discharged from said receptacle, said gallery having a drain opening, and means whereby said upper section may be rotated relative to said lower section to place said opening over said compartments selectively to deliver water thereto.

10 15 In testimony whereof I have hereunto set my hand.

GEORGE W. DUNHAM.
